UNITED STATES PATENT OFFICE

LOUIS M. PLANSOEN, OF GARFIELD, NEW JERSEY

TABLE COVER AND PROTECTOR

Application filed June 11, 1931. Serial No. 543,687.

This invention relates to an improved table cover and protector, the object being to provide a construction to be used to cover highly polished dining and other tables whereby heavy or hot dishes or other objects cannot injure the wood or high polish of the table.

Another object of the invention is to provide an improved protecting sheet for tables or other surfaces, the structure including means for presenting a soft member to the protected surface and also means for protecting and insulating the protected surface against injury by heavy weights or by hot articles.

Another object, more specifically, is to provide a sheet material which may be used for protecting highly polished tables or for other purposes, a material presenting a plurality of layers of different material acting in various capacities for protecting a given surface and at the same time presenting an added surface which will give a pleasing appearance.

In the accompanying drawing,

The figure is a perspective view of a small section of a cover embodying the invention.

Referring to the accompanying drawing by numerals, 1 indicates a top or outside layer which is formed of artificial leather, while the central layer 2 is preferably formed from a combination of rubber and asbestos mixed and vulcanized together. The bottom layer 3 is preferably of felt, either wool or cotton, or a mixture of these materials, or in fact any material which will present a yielding and soft surface having the nature of wool felt whereby it may rest on a highly polished table or other surface without injuring the same.

The artificial leather layer 1 is cemented by any desired adhesive to the layer 2 and the layer 2 in turn is cemented by any desired cement to the layer 3. Preferably a good grade of rubber cement of pyroxylin is used to connect the various layers together. The artificial leather layer 1 may be provided with a pyroxylin coating in the usual manner or a linseed oil coating where fire proofing is not necessary. However,

where it is desired to make the same fire-proof, or substantially fire-proof, an acetate coating is used. In addition, the upper surface of the layer 1 may be printed or embossed to represent high grade wood as, for instance, walnut. Where the device is used as a cover for tables, preferably the outer surface of layer 1 is grained and colored to represent the wood of the table. If the table is a walnut table, then a covering and protector having an imitation walnut surface will be used, but if the table should be oak, the same kind of a cover is used but the leather layer 1 is provided with a grain representing oak.

In forming the rubber and asbestos layer 2 which acts as a resilient cushion and also a heat insulator the same may be made from sheet or ground asbestos mixed with crude rubber. Preferably the crude rubber, after being mixed with the asbestos, is vulcanized, though this is not essential.

It is to be understood that the various layers may be of any desired thickness, but for practical purposes, it has been found that the three layers may be made to present the combined thickness of $\frac{3}{16}$ of an inch and secure very desirable results, though $\frac{1}{4}$ of an inch is not objectionable when used to protect an ordinary dining table.

While the cover and protector is designed particularly for dining room tables, it may be used in many other places and for other purposes without departing from the spirit of the invention.

I claim:

A protecting sheet article comprising an independent felt sheet, an independent sheet of resilient material consisting of ground asbestos and raw rubber, a layer of adhesive connecting said felt sheet and said sheet of resilient material, a sheet of artificial leather, a layer of cement connecting said sheet of resilient material and said artificial leather, and a fireproof layer on the outer surface of said artificial leather.
